EYEGLASS HOLDER

Stanley J. Leverence, Chicago, Ill.

Application October 20, 1955, Serial No. 38,480

Term of patent 3½ years

(Cl. D57—1)

Fig. 2.

Figure 1 is a perspective view of an eyeglass holder showing my new design and as it appears from the forward side thereof, and

I claim:

The ornamental design for an eyeglass holder, substantially as shown.
